Patented Aug. 25, 1914.

UNITED STATES PATENT OFFICE.

WILLIAM D. RUSSELL, OF FORT WORTH, TEXAS.

CAR-FENDER.

1,108,869.

Specification of Letters Patent. Patented Aug. 25, 1914.

Application filed July 26, 1912. Serial No. 711,722.

To all whom it may concern:

Be it known that I, WILLIAM D. RUSSELL, a citizen of the United States, residing at Fort Worth, in the county of Tarrant and State of Texas, have invented certain new and useful Improvements in Car-Fenders, of which the following is a specification.

My invention relates to new and useful improvements in street car fenders. Its object is to provide a fender adapted to be fitted to an extremity of a street car, and adapted to undergo an automatic swinging motion when an obstacle is encountered, which motion will tend to sweep the obstacle from the track of the car.

The object of the invention more specifically stated is to provide a fender comprising two correlated members each forming a quadrant of a circle, and each having its outer extremity provided with a vertical axis of rotation, the fender being so correlated with the piston of an air cylinder, that an automatic displacement of the piston will result when the fender encounters an obstacle, said displacement resulting in an angular displacement of the two fender members about their pivotal axes, which displacement will sweep the obstacle from the track of the car.

Finally the object of the invention is to provide a device of the character described that will be strong, durable, simple and efficient and comparatively easy to construct, and one that will not be likely to get out of working order.

With these and various other objects in view, my invention has relation to certain novel features of construction and operation, an example of which is described in the following specification, and illustrated in the accompanying drawing, wherein:

Figure 1 is a plan view of my fender together with the frame work and running gear of a car, the body of the car being removed. The car frame is shown equipped at both ends with the herein described fender, the fender at one extremity being shown in its normal position, and at the other extremity being shown swung to the position occupied after an obstacle has been encountered. Fig. 2 is a side elevation of a street car equipped at both ends with the herein described fender, which is shown in its normal position. Fig. 3 is a detailed view in elevation showing a portion of one of the two members which comprise each

fender. Fig. 4 is a fragmentary plan view showing the mechanism which establishes the relation between the compressed air system of the car and the fender. Fig. 5 is a detailed sectional view showing a portion of the same mechanism, the section being taken upon the line $y-y$ of Fig. 1.

In the drawings the numeral 1 designates the supporting frame of a traction car of ordinary construction. This frame has the usual arcuate ends. At each side of each end of the frame, a vertical hinge rod 2 is mounted and has its upper end bearing in the underside of the frame and its lower end supported in a hanger 3, the latter depending from the frame, as shown in Fig. 2.

At each end of the frame 1 a pair of fender frames each comprising arcuate members 4 and 5 respectively, are mounted on the rods 2 and arranged to swing. The respective members 4 and 5 at each side of the frame are tied together by vertical rods 6. The fender frames are equal in length and normally lie contiguous to the arcuate ends of the car frame 1 and have their free ends abutting at the center of said car frame ends. The fender frames normally lying under the arcuate ends of the frame are free to be swung outward as shown in Fig. 1.

Adjacent to the lower extremity of each vertical rod 2, a horizontal pin 7 projects outwardly from the correlated member 5. Each of the pins 7 furnishes a pivotal support for a horizontal arcuate fender member 8, which member is gradually increased in width from its pivot point to its free end. Each fender member 8 is normally supported in a horizontal position by means of a pair of vertical rods 9, which have their lower extremities secured to the inner edge portion of said fender member. These rods are mounted in a pair of side bearings 10, secured to the members 4 and 5. The vertical rods 9 have their upper extremities projecting slightly beyond the uppermost side bearings 10, and each projecting rod portion carries a coiled spring 11 suitably confined thereon, whereby said rod and the fender member are resiliently sustained. The two rods 9, adjacent to the free ends of each pair of members 8, have their upper extremities bent at right angles and projecting a slight distance inwardly over the frame 1 as indicated in the drawing.

at 12. When a pair of fender members are in their normal position beneath the end of the frame 1, the free ends of the members 12 are immediately over a plate 13, carried by one arm of a bell crank 14. The pivot pin of the bell crank is supported at the rear extremity of an inwardly projecting bracket member 15, which has its other end rigidly mounted upon the center of a curved beam 16 extending beneath the arcuate end of the frame 1. From the other arm of the bell crank 14 a rod 17 is extended inwardly under the frame 1 and is so connected with an air valve 18 as to control the same through a longitudinal displacement.

The valves 18 are interposed in an air pipe 19 adapted to control the passage of air from a compressed air tank 20 to air cylinders 21, centrally mounted beneath the car longitudinal thereof. A piston 22 is adapted to undergo a sliding displacement within each cylinder 21, and has connection with a piston rod 23, which rod has its outer extremity pivotally attached to a pair of curved swinging links 24, one extending to the free end portion of each member 4, a description of the operation of the fender members at one end of the car sufficing for both.

In the operation of the above described device, when a person or an obstacle of any kind is struck by the car, the weight of the person or obstacle coming upon either one or both of the fender members 8 will produce a downward angular displacement of either or both of said members, the pivotal mounting of the members upon the pins 7 making such a displacement possible. The amount of downward displacement to which the fender members 8 may be subjected is limited by the amount of compression adapted to take place in the springs 11. The rods 9, since their lower extremities have connection with the fender members, will also be subjected to a slight downward displacement. The downward displacement of the two rods 9, which have their upper portions 12 bent rearwardly will cause the extremities of said portions 12 to exert a downward pressure upon the plate 13, thereby subjecting the bell crank 14 to a rocking motion, which will result in a rearward displacement of the rod 17. This rearward displacement of the rod 17 will be sufficient to open the valve 18 and admit compressed air to the cylinder 21. Consequently the piston 22, which normally occupies a position at the one extremity of the cylinder 21, will be displaced to the other extremity of said cylinder, communicating a corresponding motion to the piston rod 23. Since the inner extremities of the curved links 24 are pivotally attached to the outer end of the piston rod 23, they will be made to diverge

from each other, and will thus produce an outward angular displacement of the two fender frames carrying the fender members 8. During such outward displacement of said frame, the person or obstacle lying upon either of the fender members 8 or in contact with the same will be swept from the path of the car. A tank similar to the tank 20 forms a part of the air brake equipment of all modern street cars which are also provided with means, not shown for compressing the air in such tank. The tank 20 is adapted to be charged with compressed air through a pipe 25 extending transversely from said tank and communicating with a three-way valve 26. Said valve also has communication with two pipes 27 and 28, one of which leads to an air compressor and the other to the cylinder which operates the brakes. When the valve 18 is opened admitting air to the cylinder 21, the consequent lowering of the air pressure in the tank 20 causes the air brakes to be automatically set. Thus it is apparent that when any person or object is struck by the car, equipped with the herein described fender, the air brakes will be automatically set and will stop the car, and simultaneously, the two members comprising the fender will swing apart, sweeping the person or object from the path of the car. In case for any reason, the person or object struck is not swept aside by the fender, a further safeguard is provided in the nature of a heavy mesh wire screen 29, extending downwardly from the curved end portion of the frame 1, and having its lower edge spaced a short distance above the track. This screen will catch any person or object that passes the fender, and will effectually prevent such person or object from passing beneath the car wheels.

The invention is presented as including all such modifications and changes as properly come within the scope of the following claims:

What I claim is:

1. In a device of the character described, the combination with a pair of fender frames mounted upon the end of a street car frame, of means having the nature of vertical pivots for supporting the ends of the fender frames at each side of the car frame whereby said frames may be swung laterally from each other, a device arranged to swing the fender frames laterally with relation to the longitudinal center of the car frame, an air cylinder, a piston operating in the cylinder and connected to the said device, a valve controlling the passage of air into the cylinder, a valve operating device, and depressible parts carried by the fender frames having means for engaging the valve operating device.

2. In a device of the character described,

- the combination with a street car frame, of a pair of fender frames mounted at one extremity of the car frame, a vertical pivotal axis for one end of each fender frame, the adjacent ends of the fender frames being free to be swung, a cylinder and piston rod centrally mounted beneath the car frame longitudinally thereof, a valve controlling the passage of air into said cylinder, a rod adapted to actuate said valve extending from the valve to the extremity of the car frame at which the fender frames are located, a bell-crank lever having one arm connected to the actuating rod, and means correlating the bell-crank lever with each fender frame whereby a downward displacement of said means swings the bell-crank lever. 5
3. In a device of the character described, the combination with a car frame, of a pair of fender frames having their adjacent ends free and their opposite ends pivoted on the car frame, a spring sustained fender part mounted on each fender frame, a valve actuating device mounted on the car frame, means for operating the actuating device connected to the spring sustained part of each fender frame and normally out of engagement with said device, an air cylinder, 10 15 20 25
- a piston working in the cylinder and connected to the fender frames, a valve controlling the passage of air to the cylinder, and a connection between the valve and the valve actuating device. 30
4. In a device of the character described, the combination with a car frame, of a pair of fender frames having their adjacent ends free and their opposite ends pivoted on the car frame, a spring sustained fender part mounted on each fender frame, a bell crank lever mounted on the car frame, rods connected to the spring sustained parts of the fender frames and having projections extending over the bell-crank lever, an air cylinder mounted on the car frame, a piston working in the cylinder, links having pivoted connection at their extremities with the fender frames and the piston, a valve controlling the supply of air to the cylinder, and a connection between the valve and the bell-crank lever. 35 40 45 50

In testimony whereof I have signed my name to this specification in the presence of two subscribing witnesses.

WILLIAM D. RUSSELL.
